(57) **CLAIM**

The ornamental design for a palette, as shown and described.

DESCRIPTION

FIG. 1 is a perspective view of a palette of the present invention in an open state, wherein the rotatable inner plate is unfolded,

FIG. 2 is a front view of FIG. 1.

FIG. 3 is a rear view of FIG. 1.

FIG. 4 is a left side view of FIG. 1.

FIG. 5 is a right side view of FIG. 1.

FIG. 6 is a top plan view of FIG. 1.

FIG. 7 is a bottom plan view of FIG. 1.

FIG. 8 is a perspective view of the palette of the present invention in a closed state.

FIG. 9 is a front view of FIG. 8.

FIG. 10 is a rear view of FIG. 8.

FIG. 11 is a left side view of FIG. 8.

FIG. 12 is a right side view of FIG. 8.

FIG. 13 is a top plan view of FIG. 8.

FIG. 14 is a bottom plan view of FIG. 8.

FIG. 15 is another perspective view of FIG. 1, wherein the rotatable inner plate is folded; and,

FIG. 16 is an exploded view of FIG. 1 wherein ink cases are installed in the palette.

The broken lines in the figures illustrate portions of the palette that form no part of the claimed design.

1 Claim, 16 Drawing Sheets
